UNITED STATES PATENT OFFICE.

KARL A. SIMMON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

INSULATOR.

1,246,481.

Specification of Letters Patent. Patented Nov. 13, 1917.

Application filed December 9, 1916. Serial No. 136,013.

To all whom it may concern:

Be it known that I, KARL A. SIMMON, a citizen of the United States, and a resident of Edgewood Park, in the county of Allegheny and State of Pennsylvania, have invented a new and useful Improvement in Insulators, of which the following is a specification.

My invention relates to electrical insulators and particularly to strain insulators.

One object of my invention is to provide a strain insulator which will withstand high-potential stresses without rupture of the insulating material embodied therein and which will be inexpensive to manufacture.

Another object of my invention is to provide an insulator in which the gaps between the various conducting members making up the insulator are arranged in series-circuit relation and in which the mechanical stress between the insulator parts is taken up by a compressive stress in the insulation.

A further object of my invention is to provide insulator parts, various numbers of which may be assembled together to provide insulators for various voltages.

Heretofore, insulators have been provided which had a plurality of gaps in series-circuit relation between the conducting members embodied in the insulator but such insulators have been relatively expensive to manufacture, and the insulating material connecting the parts of the insulator has been subjected to a tensile stress when force was applied to the insulator.

My invention provides an insulator in which the gaps between the conducting members embodied in the insulator are arranged in a series-circuit relation. Furthermore, the parts of the insulator are so designed that various numbers of parts may be assembled to provide insulators for various voltages.

Figure 1 of the accompanying drawing is a sectional view of an insulator constructed in accordance with my invention, and Fig. 2 is a sectional view of a modification of my invention.

The insulator shown in the drawing comprises connecting members 1 and 2, a member 3 interposed between the connecting members 1 and 2, clamping members 4 and 5, insulation 6, and a protective casing 7.

The connecting members 1 and 2 are severally provided with enlarged inner end portions 10 which are incased in insulation 11, and with a threaded socket 12 by means of which the connecting members may be secured to other insulators or to conductors which are electrically separated by the insulator. The member 3, which may be cylindrical in form, is provided with enlarged end portions 13 and 14 which are also respectively incased in insulation 11. The members 1, 2 and 3 are assembled in end-to-end relation, and the adjacent enlarged insulated portions 10 and 13 and 10 and 14 are respectively incased by members 4 and 5 which clamp the members 1 and 3, and 2 and 3 together into a rigid unit. An insulating disk 15 is provided to electrically separate the clamping members 4 and 5. A groove 16 is provided in the inner side of the disk 15 in order to increase the creepage distance between members 4 and 5. The assembled insulator parts 1, 2, 3, 4, and 5 are embedded in the insulation 6 and are surrounded by the protective insulating casing 7 to mechanically protect the insulator parts.

It will be understood, from the above description, that the various parts constituting the insulator will severally constitute condenser plates and will distribute the voltage stress which is applied across the members 1 and 2. It should also be noted that the member 3 is of such construction that any desired number of such members may be interposed between the end-connecting members 1 and 2 to provide an insulator for any desired voltage, as illustrated in Fig. 2 of the drawing. The incasing member 7 is not essential to the invention herein disclosed but, when employed, may be composed of porcelain or similar material.

Although I have described a particular embodiment of my invention, it should be understood that various modifications of the insulator may be constructed without departing from the spirit and scope of my invention. I desire that only such limitations shall be imposed as are indicated in the appended claims.

I claim as my invention:

1. A unitary insulator comprising end members each having an enlarged end portion, a metallic member interposed between said end members and insulated therefrom,

and insulated metallic means for clamping said members together.

2. A unitary insulator comprising end members each having an enlarged end portion, a metallic member having enlarged ends and interposed between said end members and insulated therefrom, and a metallic shell for incasing adjacent enlarged portions and clamping the same together.
- 10 3. A unitary insulator comprising end members each having an enlarged end portion, a metallic member having enlarged ends and interposed between said end members and insulated therefrom, and insulated metallic members for respectively incasing each pair of adjacent enlarged end portions to clamp said members together.
- 20 4. A unitary insulator comprising connecting members having enlarged inner end portions, an interposed member having enlarged ends, and incasing members for respectively clamping said end portions together, all of said members being embedded in insulating material and insulated from all 25 other of said members.
- 30 5. An insulator comprising end members respectively having an enlarged end portion surrounded by insulating material, a member having enlarged ends and similarly insulated, said members being assembled in end-to-end relation, with said enlarged portions adjacent, and incasing members for clamping said adjacent enlarged portions together.
- 35 6. An insulator comprising end members respectively having an enlarged end portion surrounded by insulating material, a member having enlarged ends and similarly insulated, said members being assembled in 40 end-to-end relation, with said enlarged portions adjacent, and a clamping member for holding one pair of said adjacent enlarged portions together.
- 45 7. An insulator comprising end members respectively having enlarged end portions surrounded by insulating material, a member having enlarged ends and similarly insulated, said members being assembled in end-to-end relation, with said enlarged por-

tions adjacent, and metallic members for respectively clamping said adjacent end portions together, said metallic members being embedded in insulating material.

8. An insulator comprising end members respectively having enlarged end portions surrounded by insulating material, a member having enlarged ends and similarly insulated, said members being assembled in end-to-end relation, with said enlarged portions adjacent, incasing members for clamping said adjacent enlarged portions together, said incasing members being embedded in insulation, and an insulating jacket surrounding all of said members.

9. An insulator comprising end members respectively having enlarged end portions, a member having enlarged ends and interposed between said end members, said members being assembled with said enlarged portions adjacent, an incasing member for clamping said adjacent enlarged portions together, and means for insulating each of said members.

10. An insulator comprising a metallic connecting member having an enlarged end portion, a member having enlarged ends, the enlarged portions of said members being insulated and assembled in end-to-end relation, with the enlarged portions adjacent, a metallic member for clamping said enlarged portions together, and insulating material surrounding all of said members.

11. An insulator comprising end members respectively having enlarged end portions, a member having enlarged ends and interposed between said end members, said members being assembled in end-to-end relation, an incasing member for clamping each pair of enlarged end portions together, an insulating disk having a grooved inner surface and interposed between said incasing members, and means for insulating each of said members.

In testimony whereof, I have hereunto subscribed my name this 24th day of Nov. 1916.

KARL A. SIMMON.
